UNITED STATES PATENT OFFICE.

CHARLES C. PENFOLD, OF BUFFALO, NEW YORK.

DESIGN FOR A BADGE.

SPECIFICATION forming part of Design No. 36,410, dated July 7, 1903.

Application filed May 28, 1903. Serial No. 158,553. Term of patent 3½ years

To all whom it may concern:

Be it known that I, CHARLES C. PENFOLD, a citizen of the United States, and a resident of Buffalo, in the county of Erie and State of New York, have invented and produced a new, original, and ornamental Design for Badges, of which the following is a specification, reference being had to the accompanying drawing, forming a part thereof.

My invention consists of a new, original, and ornamental design for a badge, which embodies the combination of a fleur-de-lis

and an eagle, as shown in the figure of the accompanying drawing.

I claim—

The ornamental design for a badge, as shown.

In testimony that I claim the foregoing as my own I affix my signature in the presence of two subscribing witnesses.

CHARLES C. PENFOLD.
